UNITED STATES PATENT OFFICE.

ABRAM KEACH, OF SOMERVILLE, MASSACHUSETTS.

RULING-MACHINE.

SPECIFICATION forming part of Letters Patent No. 730,923, dated June 16, 1903.

Application filed January 31, 1903. Serial No. 141,342. (No model.)

To all whom it may concern:

Be it known that I, ABRAM KEACH, a citizen of the United States, residing at Somerville, in the county of Middlesex and State 5 of Massachusetts, have invented certain new and useful Improvements in Ruling-Machines; and I do hereby declare the following to be a full, clear, and exact description of the invention, such as will enable others skilled 10 in the art to which it appertains to make and use the same.

This invention relates to machines for ruling paper; and it consists in the novel construction and combination of the parts hereinafter fully described and claimed.

In the drawings, Figure 1 is a side view of the machine. Fig. 2 is a detail side view of one of the cam-plates. Fig. 3 is a plan view of the machine. Fig. 4 is a cross-section 20 through the cam-plate shown in Fig. 2.

A is the frame of the machine, provided with a table *a'* for the sheets of paper to rest on before being ruled.

B is the impression-cylinder, journaled in 25 the frame at one end of the table and provided with means for revolving it, such as a belt-pulley *b*, secured on its shaft *b'*.

C is the ruling-shaft, provided with a series 30 of ruling-disks *c*, arranged over the cylinder B at any preferred distances from each other. The shaft C is journaled in bearings *c'*, which slide in vertical slots D in the frame A.

E is the inking-cylinder, arranged over the shaft C and journaled in bearings *e*, which 35 slide in the said slots D.

F represents disks on the end of the ruling-shaft C, and G represents cam-disks secured on the end portions of the shaft *b'* of the impression-cylinder. Each disk G is provided 40 with one or more cam-plates *g*, which are removable and adjustable, and these cam-plates raise the ruling-disks clear of the impression-cylinder when there is no paper on the said cylinder.

H represents cam-disks, also secured to the shaft *b'* and provided with the cam-plates *h*.

I is a feed-roller journaled in arms *i*, which are pivoted on pins *i'*, projecting from the frame A. Disks *j* are mounted on the ends 50 of the feed-roller and are raised by the cam-plates *g* just before the said cam-plates raise

the ruling-shaft. The feed-roller is pressed downward by springs *j'* or by gravity.

K is a gage-bar arranged close in front of the feed-roller shaft and having its ends secured to the arms *k*, which are pivoted on the said pins *i'*. Disks *k'* are also carried by the arms *k* and are operated by the said cam-plates *h*. The gage-bar is pressed downward by gravity or by springs *m*. When the gage-bar is down on the impression-cylinder, a sheet of paper is slid against it and is thus alined. The motion of the impression-cylinder then causes the cam-plates *h* to raise the gage-bar and the cam-plates *g* to drop the feed-roller simultaneously upon the edge of 60 the sheet of paper, the ruling-disks at this time being held clear of the impression-cylinder by the cam-plates *g*. The paper begins to pass over the impression-cylinder, and as 65 soon as it comes under the ruling-disks these disks are dropped by the continued motion of the cam-plates *g*. The paper is then ruled by contact with the ruling-disks. When the paper leaves the impression-cylinder the cam-plates *g* raise first the feed-roller and then 70 the ruling-disks, and the gage is dropped by the cam-plates *h* directly the feed-roller is raised.

What I claim is—

1. In a ruling-machine, the combination, with a frame provided with a table, of an impression-cylinder provided with a shaft which is journaled in the frame at one end of the table, a ruling-shaft provided with 85 ruling-disks, and an inking-roller, both arranged over the said cylinder, two cam-disks secured on each end of the said cylinder-shaft and provided respectively with cam-plates *g* and *h*, disks on the said ruling-shaft 90 in the path of the cam-plates *g*, a vertically-movable feed-roller provided with disks also arranged in the path of the cam-plates *g*, and a vertically-movable gage-bar provided with disks arranged in the path of the cam-plates 95 *h*, said cam-plates *g* and *h* being arranged to operate alternately, substantially as set forth.

2. In a ruling-machine, the combination, with a frame provided with a table, of an impression-cylinder provided with a shaft 100 which is journaled in the frame at one end of the table, a ruling-shaft provided with

ruling-disks, and an inking-roller, both journaled over the said cylinder, two cam-disks secured on each end of the said cylinder-shaft and provided respectively with cam-
5 plates *g* and *h*, disks on the said ruling-shaft in the path of the said cam-plates *g*, arms *i* pivoted to the frame, a feed-roller journaled in the arms *i* and provided with disks ar-
ranged in the path of the cam-plates *g*, arms
10 *k* also pivoted to the frame and provided

with disks arranged in the path of the cam-
plates *h*, and a gage-bar carried by the arms
k, said cam-plates *g* and *h* being arranged to
operate alternately, substantially as set forth.

In testimony whereof I affix my signature **15**
in presence of two witnesses.

ABRAM KEACH.
